UNITED STATES PATENT OFFICE.

ORREN I. MASSEY, OF ELK CITY, OKLAHOMA, ASSIGNOR OF ONE-HALF TO SAMUEL WILLIAMS, OF ELK CITY, OKLAHOMA.

CLOTHING AND PACKAGE CARRIER.

Application filed August 28, 1925. Serial No. 53,079.

My invention relates to carriers and more particularly to carriers for use in vehicles for carrying coats or other clothing and packages or luggage; and the object is to provide a simple device with which the traveling people may take care of clothing or packages in vehicles and which device can be attached to the interior of the vehicle without interference with the passengers and which can be quickly attached to or detached from the vehicle and which can be furnished at small cost. Other objects and advantages will be fully explained in the following description and the invention will be more particularly pointed out in the claims.

Reference is had to the accompanying drawings which form a part of this application.

Fig. 1 is a broken view of a car, showing a carrier attached to the back part and one attached to the side near the top. Fig. 2 is a plan view of the device, partly broken. Fig. 3 is an enlarged detail view, partly in section.

Similar characters of reference are used to indicate the same parts throughout the several views.

This carrier is provided with a rectangular or other shaped frame, preferably of wire or rods but it is apparent that the frame may be made of other material. The frame 1 extends on all sides of the device and a sheet of cloth 2 is attached to the frame 1 by lapping the edges of the frame over the frame rod 1 and sewing the lapped portion to the body of the sheet of cloth 2. The cloth 2 may be canvas, ducking, leather, or imitation leather, thin metal or other suitable material. The frame 1 is hingedly connected to the vehicle at some distance from the top of the vehicle by means of screw eyes 3 which catch around the wire or rod 1 and which are screwed into some solid part of the vehicle frame. The screw eyes 3 are at one edge of the carrier and the free edge 4 is held yieldingly against the top of the vehicle so that it may be pulled down for placing clothing or packages on top of the carrier. Spiral springs 5 are attached to the corners of the free or front edge 4 of the carrier and extended towards the back edge thereof. The springs 5 are provided with eyes 6 which

are caught on hooks 7 which are screwed into some solid part of the vehicle body frame. 55 The carrier is provided with side members 8 which may be continuations of the cloth of sheet 2. The edges of the material of the side members 8 are lapped over the springs 5 and sewed or otherwise attached to the members 8, the lapped edges being sufficiently large so that the free operation of the springs 5 will not be interfered with, the springs 5 moving freely in the pockets formed by the lapped portions. 60 65

The device is installed by hanging the back edges on the hooks 3 and then catching the eyes 6 on the hooks 7. The springs 5 must have sufficient tension to hold the front edge of the carrier up against the top of the vehicle and to support the articles to be carried by the carrier. The clothing or other article may be placed on the carrier by simply pulling down the front edge and placing the article on top of the carrier. 70 75 The springs 5 will press the carrier up and hold the articles against the top of the vehicle.

It is apparent that the improved carrier may be attached to the back part of the vehicle or to the sides of the vehicle, as shown in Fig. 1.

What I claim, is,—

1. A clothing and package carrier comprising a frame and a sheet of supporting material attached to said frame, flexible side members attached to the lateral edges of said frame, means for hingedly connecting one edge of the carrier to a vehicle frame, and yielding means normally inclosed 80 in said side members for holding the free edge of said carrier against the top of the vehicle. 85 90

2. A clothing and package carrier comprising a frame and a sheet of supporting material attached to said frame, means for hingedly connecting one edge of the carrier to a vehicle frame, and means for yieldingly holding the free edge against the top of the vehicle consisting of coil springs attached 95 to the corners of the free edge of said carrier and provided with eyes at the other ends, and hooks attached to the vehicle frame to receive and hold said spring by means of said eyes. 100 105

3. A clothing and package carrier com-

prising a frame, a sheet of supporting material having its edges folded over said frame and attached to the body of the sheet, means for hingedly connecting one edge of said carrier to a vehicle frame, resilient means for yieldingly holding the free edge of said carrier against the top of the vehicle,

and flexible members attached to the lateral edges of said frame and substantially inclosing said resilient means. 10

In testimony whereof, I set my hand, this 22 day of August, 1925.

ORREN I. MASSEY.
